CLAIM

The ornamental design for an electrocardiography monitor, as shown and described.

DESCRIPTION

FIG. 1 is a perspective view showing an electrocardiography monitor.

FIG. 2 is a top plan view of the electrocardiography monitor. FIG. 3 is a bottom plan view of the electrocardiography monitor.

FIG. 4 is a front elevational view of the electrocardiography monitor.

FIG. 5 is a rear elevational view of the electrocardiography monitor.

FIG. 6 is a right elevational view of the electrocardiography monitor.

FIG. 7 is a left elevational view of the electrocardiography monitor; and,

FIG. 8 is another perspective view thereof, in which the electrocardiography monitor is shown in an example environment, as shown in broken lines.

The broken lines immediately adjacent the claimed surface represent the bounds of the claim, and all other broken lines represent environment; the broken lines form no part of the claimed design.
